UNITED STATES PATENT OFFICE.

EDWARD B. HESS, OF BROOKLYN, NEW YORK, ASSIGNOR TO ROYAL TYPEWRITER COMPANY, INC., OF NEW YORK, N. Y., A CORPORATION OF NEW YORK.

PACKING-BOX FOR TYPE-WRITING AND LIKE MACHINES.

1,168,632.

Specification of Letters Patent.

Patented Jan. 18, 1916.

Application filed January 5, 1914. Serial No. 810,281.

To all whom it may concern:

Be it known that I, EDWARD B. HESS, a citizen of the United States, residing in Brooklyn, in the county of Kings and State of New York, have invented certain new and useful Improvements in Packing-Boxes for Type-Writing and like Machines, of which the following is a specification.

The object of this invention is to equip 10 a packing box with means of simple construction for securely holding in place a typewriting or like machine in such manner that it may be shipped without danger of injury, such holding means being easily applied and as easily withdrawn to permit the 15 removal of the machine from the box.

In carrying out my invention I employ a packing box of ordinary construction provided with a removable lid and I provide a 20 skid or base frame on which the machine rests. The skid is provided with feet of some soft material, such as felt to afford a cushioning support to the machine.

In order to hold the machine tightly 25 against sidewise movement, I provide blocks which are secured to the sides of the box and are provided with cushions of felt or similar material which bear against the sides of the machine-frame and in order to 30 prevent endwise movement of the machine and to cushion it, a pad is interposed between the front of the box and the front of the machine and against the pad the machine-frame is forced by blocks engaging 35 the rear end of the machine-frame and the rear end of the box. These blocks carry 40 cushions and they are pressed against the machine-frame by a locking board which slides vertically in grooves in the box and is held in place by the box lid when the latter is applied. I also employ a locking board at the front of the box which slides 45 vertically in grooves in the box and it is provided on its lower edge with a cushion bearing on the machine-frame. Said front board is held in place by the box lid.

In the accompanying drawings, Figure 1 is a plan view of a packing box equipped 50 with my improvements with the box lid removed and showing how the frame of a typewriting machine is held in place in the box. A portion of the front locking board is shown broken away. Fig. 2 is a perspective view of the box with the lid removed 55 and with parts broken away, the packing

and locking devices also being shown in perspective and some parts of these devices being broken away while others are shown in dotted lines. Fig. 3 shows a side elevation of the box with the lid applied and 60 with one side thereof with certain parts attached thereto removed. It also shows how the frame of a typewriting machine is held in place. Fig. 4 is a perspective view of the skid on which the machine rests within the 65 box. Figs. 5 to 10 inclusive are perspective views illustrating respectively the following parts of the locking mechanism, viz., the front locking board, the rear locking board, the pad against which the front end of the 70 machine-frame bears, one of the cushion blocks for one side of the machine-frame and a pair of cushioning blocks for the other side of the frame, and lastly one of the blocks employed to hold down the rear 75 portion of the machine-frame and to force the frame against the front pad.

I have shown in the drawings the frame of a typewriting machine of well known construction and have indicated different 80 parts of this frame by the letter A.

The box B is of ordinary construction, being square and provided with a removable lid b (Fig. 3).

The machine rests on a skid C shown separately in Fig. 4 and consisting of parallel sides c connected by end pieces c'. The sides are notched at c' to receive the feet a of the machine, and at the corners of the skid I provide feet c² of felt or other similar material.

In order to prevent sidewise movement of the machine, I provide on one side thereof two cushioning blocks D, one of which is shown separately in perspective in Fig. 8. 95 Each such block is preferably of rectangular form and carries a cushion or pad d which bears against the base of the machine-frame as shown in Figs. 1, 2 and 3. These blocks are attached to the sides of the box by fastening devices, as shown at d'. On the opposite side of the box I provide two pairs of locking blocks E, E' (Fig. 9). Each pair consists of two wedge shaped members E, E', one of which carries a pad e. The pads of the members E' bear against the side of the machine-frame when the members E are forced downward between the side of the box and the face of the member E'. This causes the machine frame to be tightly held 110

in place against sidewise movement. After being thus wedged the members E are attached to the side of the box by the fastening devices e'.

5 In order to prevent endwise movement of the machine, I interpose between the front of the frame and the front of the box a pad F which may be secured to the front of the box, and in order to press the frame against this pad I employ two blocks G (Fig. 10) which bear against the rear of the machine-frame and the rear end of the packing box. Each block, as shown in Fig. 10, is formed with a padded recessed end g which engages 10 the machine-frame, and a beveled end g' which bears against the rear end of the packing box, and I may also provide the rear portion of each block with a pad g².

H (Fig. 6) indicates the rear locking board. It is rectangular in shape and is formed with two recesses h to receive the rear ends of the blocks G. The upper walls of these recesses are padded as shown at h' to provide cushions. The board H slides 20 vertically in grooves i formed in cleats I secured in the corners of the box at its rear end, and when the lid is applied the board H is forced downward upon the blocks G and as these blocks are inclined upwardly and rearwardly from their lower front ends they will be caused to force the machine against the front pad F and they also serve to hold 25 down the rear portion of the machine.

In order to hold down the front portion 30 of the machine, I employ a locking board J, (Fig. 5) which is rectangular in shape and is provided with a pad j on its under side. This board J slides vertically in grooves or channels k formed in cleats K arranged in 35 the opposite corners at the front of the box and secured in place by fastening devices of any suitable kind. When the box lid is applied the board J is pressed downward and holds the front portion of the machine firmly 40 in place.

The manner of packing the machine in the box has been hereinbefore indicated, and it will be understood that the machine is first 45 lowered onto the skid C between the blocks D, E, E', the blocks E being slightly elevated above their final position, or the blocks E, E' may be inserted after the machine is lowered onto the skid, but after this is done the blocks E are driven downward and serve as wedges to press the pads e against one side of the machine and cause the opposite side of the machine to press tightly against the pads d. After this the fastening devices e' are applied.

50 In order to hold the machine firmly against endwise movement the front portion of its frame is first made to bear against the pad F, then the blocks G are applied to the rear portion of the machine-frame and the beveled ends g' of these blocks are made to

bear against the rear end of the packing box, then the locking board H is lowered and the locking board J is similarly lowered, finally the lid b is applied and this lid engages the locking boards H and J forcing them downward, pressing the front end of the machine-frame against the skid and causing the inclined blocks G to be forced downward and forward, thus holding down the rear portion of the machine and causing its front portion to bear tightly against the front pad F. In this condition the box with its contained machine may be safely shipped or moved from place to place without danger of injury.

55 While I have described my invention as particularly designed for packing typewriting machines, it will be understood that some parts of the invention may be employed for packing machines of other kinds. I have shown a plurality of padded blocks for holding the machine in place, but it is obvious that single blocks may be made large enough and used for a similar purpose. Other details of the invention may also be 60 varied in well known ways.

I claim:

1. A packing box provided with stationary padded blocks to engage the sides of a machine frame, a movable block also adapted to engage one end of the frame of the machine, a locking board engaging the movable block and means for holding the locking board in place.

2. A packing box provided with stationary blocks adapted to engage one side of a machine-frame, blocks adapted to engage the opposite side of the machine frame, wedges for forcing said last mentioned blocks against the frame of the machine, movable blocks adapted to engage the frame of the machine, a locking board engaging said movable blocks and means for holding the locking board in place.

3. A packing box having a lid and provided with stationary padded blocks to engage the sides of a machine-frame, a movable block also adapted to engage one end of the frame of the machine, and a locking board engaging the movable block and held in place by the lid.

4. A packing box having a lid and provided with stationary blocks adapted to engage one side of a machine-frame, blocks adapted to engage the opposite side of the machine-frame, wedges for forcing said last mentioned blocks against the frame of the machine, movable blocks adapted to engage the frame of the machine, and a locking board engaging said movable blocks and held in place by the box lid.

5. A packing box having a lid and provided with padded blocks adapted to engage opposite sides of a machine-frame, movable blocks adapted to engage the ma- 130

chine-frame at its rear end, a locking board engaging said blocks and which is pressed downwardly by the box lid, and a locking board at the front of the box engaged by 5 the box lid and adapted to engage the front portion of the machine-frame.

6. A packing box having a lid and provided with a pad at its front end against which the front end of a machine-frame is 10 adapted to bear, an inclined block adapted to engage the rear portion of the machine-frame, and a vertically moving locking board engaging said inclined block and which is moved downwardly by the box lid.

15 7. The combination with a packing box having a lid, of a pad at one end of the box adapted to bear against the end of the frame of a machine, a block adapted to engage the opposite end of the machine-frame 20 and to be disposed in an upwardly inclined position relatively thereto, and a locking board engaging said block held in place by the box lid and acting to force the machine against the front pad.

25 8. A packing box having a lid and provided with means for preventing a machine from moving sidewise, a locking board engaged by the lid for holding down the front portion of the machine, a vertically moving locking board engaging the lid and means 30 operated by said vertically moving locking board to hold down the rear end of the ma-

chine and to force it toward the front end of the box.

9. A packing box having a lid and provided with blocks engaging the opposite sides of a machine-frame to prevent sidewise movement thereof, means for holding down the front end of the machine, a block 35 engaging the rear end of the machine-frame and means operated by the lid for moving said last mentioned block downwardly and forwardly to press the machine downward in the box and brace it against endwise movement. 40

10. A packing box having a lid and provided with a skid for supporting a machine and which carries cushioning feet, blocks adapted to engage opposite sides of the machine-frame for preventing sidewise movement thereof, means for pressing the front 45 end of the machine upon the skid, a block engaging the rear end of the machine-frame, and means acting upon said block to force the machine downward upon the skid and 50 for bracing the machine against endwise movement in the box. 55

In testimony whereof, I have hereunto subscribed my name.

EDWARD B. HESS.
